UNITED STATES PATENT OFFICE.

ERNEST P. WARNER, OF CHICAGO, ILLINOIS, ASSIGNOR TO THE WESTERN ELECTRIC COMPANY, OF SAME PLACE.

ELECTRIC-ARC LAMP.

SPECIFICATION forming part of Letters Patent No. 593,626, dated November 16, 1897.

Application filed March 16, 1897. Serial No. 627,794. (No model.)

To all whom it may concern.

Be it known that I, ERNEST P. WARNER, a citizen of the United States, residing at Chicago, in the county of Cook and State of Illinois, have invented a certain new and useful Improvement in Electric-Arc Lamps, (Case No. 64,) of which the following is a full, clear, concise, and exact description, reference being had to the accompanying drawings, forming a part of this specification.

My invention relates to an electric-arc lamp, and has for its object to provide improved means for effecting an automatic and regular feeding of the carbons to keep the carbon-points approximately the same distance apart until they are practically consumed.

In arc-lamps where the carbon is suspended from a chain or metallic ribbon it has been difficult to obtain suitable clutching mechanism which will act positively and surely to regulate the distance between the carbon-points.

In accordance with my invention the chain which upholds the stick of carbon passes over a sprocket-wheel, and electrically-operated clutching mechanism is applied to the latter when the lamp is switched into circuit, whereby the wheel is caused to rotate slightly, thus separating the carbons a short distance and establishing the arc. As the carbons are consumed and the resistance of the arc becomes greater the clutch mechanism relaxes its hold upon the sprocket-wheel, thus allowing it to be turned freely as the carbon is fed downward by its own weight until the proper length of arc is obtained, whereupon the clutch is caused to engage the sprocket-wheel and prevent further rotation thereof until the clutch is again caused to relax its hold.

The clutch which I preferably employ consists of two members rotatably mounted, the sprocket-wheel being mounted between them coaxially therewith. The two members are so linked together and mounted that when one of them, which I term the "gripping" member, is rotated by the operating mechanism of the lamp the link connections cause the members to approach each other, thus clamping the sprocket-wheel rigidly between them and preventing relative movement.

Upon further rotation of the gripping member the sprocket-wheel and the second or "releasing" member are caused to rotate therewith. Upon rotation of the gripping member in the opposite direction an arm carried by the releasing member is engaged by a stationary stop, preventing further rotation of the releasing member in that direction. If, now, the gripping member continues to rotate, the link connection between them causes the two members to separate, thus releasing the sprocket-wheel and permitting it to be turned freely.

I will describe the details of my invention more fully by reference to the accompanying drawings, in which—

Figure 1 is an elevation, partly in section, of an arc-lamp embodying my invention. Fig. 2 is a sectional elevation of the operating mechanism. Fig. 3 is a plan view of the clutch and adjacent parts. Fig. 4 is a detail plan view of the clutching members in a relaxed condition. Fig. 5 is a sectional plan view thereof. Fig. 6 is a sectional view on line 66 75 of Fig. 4.

Similar letters of reference indicate similar parts throughout the several figures.

The carbon *a* is secured at its upper end to the carbon-clamp *a'*. The chain *b* is fastened thereto and passes upward over the sprocket-wheel *c* and then downward, terminating in a weight *d*, which is adapted to slide up and down in the tube *e*. The sprocket-wheel *c* is mounted with roller-bearings *c' c'* upon the shaft *c²*, as shown in Fig. 5, and is adapted to be rotated freely thereon, except when engaged by the clutch. The shaft *c²* is mounted at either end in supports *c³ c⁴*. The clutching mechanism consists of two members, one of which, the gripping-disk *f*, is mounted to rotate upon the shaft *c²* between the sprocket-wheel *c* and the support *c³*, while the other, the releasing-disk *f'*, is likewise mounted upon the shaft *c²* between the sprocket-wheel *c* and the support *c⁴*. Each disk is provided with a carbon face *k k'*, which is brought into frictional engagement with the side of the sprocket-wheel, when the disks are caused to approach each other. Links *f² f²* are provided, which join the disks *f f'* at two approximately diametrically opposite points.

The cores of the solenoids g g are joined by a yoke-piece g' . A link h connects the middle of said yoke-piece with a lug upon the periphery of the gripping-disk f , so that when the yoke is raised the disk is rotated about the shaft c^2 . Extending outwardly from the periphery of the releasing-disk f' and mounted thereon is an arm f^3 , carrying upon its end a weight f^4 . An additional weight i is preferably suspended from the weight f^4 by a coiled spring i' .

It will be seen that when the solenoids g g are energized, drawing up their cores and the yoke-piece g' , the gripping-disk f will be caused to rotate in a clockwise direction, Fig. 2, about the shaft c^2 . Because of the link connections f^2 f^3 the releasing-disk f' , with the weighted arm mounted thereon, will be rotated also; but the weight f^4 , tending to rotate the releasing-disk f' in a contra-clockwise direction, the two disks will be caused to approach each other, their carbon faces k k' engaging with the sides of the sprocket-wheel c . This prevents movement of the latter with relation to the disks and causes it to rotate therewith, thus raising the carbon a , through the medium of the chain b , and establishing the arc. When the resistance of the arc becomes greater, the solenoids become sufficiently deenergized to permit the yoke-piece g' to drop, rotating the disk f in a contra-clockwise direction. This will at last cause the weighted arm of the releasing-disk f' to be stopped in its downward path by a stop l , mounted upon the frame of the lamp, preventing further rotation of the disk f' in that direction. Upon continued contra-clockwise rotation of the disk f the links f^2 f^3 will cause the two disks to recede from one another and release their hold upon the sides of the sprocket-wheel, which may then permit the carbon to descend by its own weight. This continues until the arc is so shortened that the solenoids g g are energized to greater strength, when the yoke is again lifted, causing the disks to again engage the sprocket-wheel and check farther descent of the carbon.

It will be seen that various modifications may be readily made by those skilled in the art, and I do not therefore desire to be understood as limiting myself to the precise construction shown; but,

Having described one form of my invention, I claim as new, and desire to secure by Letters Patent, together with all such modifications as may be made with mere skill, and with only those limitations expressed or by

law implied in view of the state of the related arts, the following:

1. In an electric-arc lamp, the combination with a chain or ribbon supporting the carbon, of a controlling-wheel over which said chain or ribbon is passed, two rotatable clutching members mounted one at either side of said controlling-wheel, link connections between said clutching members, whereby independent rotation of one of said members with relation to the other varies the distance between them, causing engagement or release of said controlling-wheel, and electromagnetic means for causing such independent rotation, thereby to effect the regulation of the lamp, substantially as described.

2. In a friction-clutch, the combination with a movable element, of clutching members rotatably mounted one at either side thereof, and link connections between said members, whereby independent rotation of one of said members varies the distance between them, causing engagement or release of said movable element according to the direction of such rotation, substantially as described.

3. The combination with a wheel whose rotation is to be controlled, of clutching-disks f f' operatively mounted one on either side of said wheel and coaxially therewith, and link connections between said disks at approximately diametrically opposite points whereby independent rotation of the disk f with relation to the disk f' varies the distance between them, causing them to engage the sides of the wheel and prevent its relative movement, or relax such engagement, according to the direction of rotation of said disk f , substantially as described.

4. The combination with a wheel whose rotation is to be controlled, of clutching-disks f f' operatively mounted one on either side of said wheel and coaxially therewith, a retarding element f^4 associated with the disk f , and link connections between said disks at approximately diametrically opposite points, whereby independent rotation of the disk f with relation to the disk f' varies the distance between them, causing them to engage the sides of the wheel and prevent its relative movement, or relax such engagement, according to the direction of rotation of said disk f , substantially as described.

In witness whereof I hereunto subscribe my name this 4th day of March, A. D. 1897.

ERNEST P. WARNER.
